ORAL LIQUID DISPENSING PACKAGE

Joseph L. Arcudi, Elizabeth, N.J., assignor to Ivers-Lee Company, Newark, N.J., a corporation of Delaware

Filed Aug. 25, 1967, Ser. No. 8,395

Term of patent 14 years

(Cl. D9—192)

Fig. 1

Fig. 2

Fig. 3

Fig. 4

FIG. 1 is a front elevation of an oral liquid dispensing package showing my new design, the rear elevation being a mirror image thereof;

FIG. 2 is a side elevation thereof, the other side being a mirror image thereof;

FIG. 3 is a top plan view thereof; and

FIG. 4 is a bottom plan view thereof.

I claim:

The ornamental design for an oral liquid dispensing package, as shown and described.
